US0D1054328S

(12) **United States Design Patent** (10) Patent No.: **US D1,054,328 S**
(45) Date of Patent: ** Dec. 17, 2024

(54) **BICYCLE FRAME**

(71) Applicant: **CASA MASFERRER S.A.**, Granollers (ES)

(72) Inventors: **Jaume Masferrer Velayos**, Granollers (ES); **Marc Ganduxé García**, Lliçà d'Amunt (ES)

(73) Assignee: **CASA MASFERRER S.A.**, Granollers (ES)

(**) Term: **15 Years**

(21) Appl. No.: **35/519,527**

(22) Filed: **Dec. 15, 2023**

(80) **Hague Agreement Data**

Int. Filing Date: **Dec. 15, 2023**

Int. Reg. No.: **DM/233918**

Int. Reg. Date: **Dec. 15, 2023**

Int. Reg. Pub. Date: **Dec. 29, 2023**

(30) **Foreign Application Priority Data**

Jun. 16, 2023 (EM) 015024866-0001
